UNITED STATES PATENT OFFICE.

GEORGE H. JENKINS, OF OAK PARK, ILLINOIS.

BOOKBINDING APPLIANCE.

1,215,160.

Specification of Letters Patent.

Patented Feb. 6, 1917.

Application filed May 11, 1914. Serial No. 837,899.

To all whom it may concern:

Be it known that I, GEORGE H. JENKINS, a citizen of the United States, residing at Oak Park, in the county of Cook and State 5 of Illinois, have invented certain new and useful Improvements in Bookbinding Appliances, of which the following is a specification.

This invention relates to an appliance for 10 evening and alining loose leaves and for compressing the edges thereof preparatory to binding the same into book form.

I have sought to provide an appliance of 15 the kind described which will be simple, inexpensive, and efficient for the purpose; to provide means for evening and alining stacks of leaves which may vary in size; and to provide means for compressing the 20 edges of the leaves to be bound, the said means serving also as guides for a punching or drilling device; and being so arranged as not to interfere with the subsequent operation of binding. The invention consists further in numerous other features of construction and 25 combinations of parts, as will more fully hereinafter appear.

In the drawings:

Figure 1 is a view in perspective from the rear side showing an embodiment of the 30 present invention;

Fig. 2 is a plan view of the guide and compression bar;

Fig. 3 is an enlarged detail of one end of the guide and compression bar;

Fig. 4 is a detail of the lower guide plate 35 and front edge of the same;

Fig. 5 is a section through the base and one evener, showing the means for advancing and holding the same in position; and

40 Figs. 6 and 7 are modifications of the means shown in Fig. 5.

In the present invention, I utilize a base 45 upon which a stack of leaves to be bound are laid in position. These leaves are alined and evened up through the instrumentality of eveners 9, supported by members 10 secured to the rear side thereof. The members secured to the laterally moving eveners carry each a rearwardly extending arm

50 11, the under face of which is provided with teeth or serrations, as appears clearly in Fig. 5. These arms 11 are arranged each to lie and fit slidingly within a slot 12 formed in the base 8, the sides of said arms engaging 55 with the walls of said slots to accurately guide the eveners in a straight line

movement. The teeth upon the under side of each of the arms 11 are arranged to engage with complementary teeth 13 formed on racks which lie within the slots 12, so that, as the eveners are moved, a successive engagement of these teeth with each other will obtain. It is intended by this arrangement, that the eveners may be moved in one direction by riding upon and over the teeth 60 of the rack, but not in the opposite direction, unless by elevating the evener and arm 11, the teeth of the rack are disengaged.

Instead of the means shown in Fig. 5 for advancing the eveners, the arrangement 70 illustrated in Fig. 6 may be employed. This differs only in that the arm 11 is carried forwardly of the block so that a stack of leaves when laid upon the base lie directly over the arm, the weight of the paper preventing its disengagement from the teeth 13.

I have also shown an evener 9 which moves 75 in a longitudinal direction, or to and from the rearward and forward edges of the base 8. The means for accomplishing this movement may be the same as those described for the other laterally moving eveners, but I prefer to use means as follows. The supporting arm 11 is provided with a tongue 14 which projects into a slot 12 corresponding 80 with those for the other arms 11. Instead of the rack and teeth, however, I utilize a threaded stem 15 which engages with the tongue 14, a wheel 16 for manipulating the same being located conveniently at the rear 85 edge of the base 8. It is manifest that rotation of this stem causes a positive movement of this evener in a forward or rearward direction according to the nature of the manipulations effected.

Upon the forward edge of the base 8 is a plate 17 carrying upwardly extending posts 18 screw-threaded to receive each a thumb nut 19. A plate 20 is also shown, corresponding closely in size to the plate 17 and 90 free to move vertically upon the posts 18. By providing a spring clip 21 at each end of the plate 20 to engage with the thumb nut, this plate is maintained in elevated position whenever desired. I have shown a 95 plurality of bosses 22 extending upwardly from the plate 20 within which are circular openings 23 for purposes to be hereafter explained. Interconnecting each of these openings 23 is a slot 24 extending continuously between the outermost bosses. The plate 17 is similarly provided with a slot 24,

with this difference, however, that I do not deem it necessary to arrange enlarged openings 23, such as appear in the plate 20, but prefer to utilize a single widened slot of substantially equal length with the narrow slot in the plate 20. Beneath the plate 17, the base 8 is slotted as at 25, corresponding with the slot in the plate 17, for purposes to be hereafter explained.

10 In operation, the binding appliance is used substantially as follows. The eveners are adjusted in position to receive the sheets of paper to be bound, as well as the covers therefor, these being laid in place either a few or a large number at one time. The edges of the sheets which are to be bound are alined, with the plate 17, the evener adjacent the rear edge of the base coöperating for this purpose. By the means above described, the paper leaves are accurately squared and alined for binding purposes.

Thereafter the plate 20 is brought down upon the edges of the leaves, and through manipulation of the thumb-screws 19, a compression of the leaves is effected. In the arrangement shown, a hand drill may be employed to bore through the edges of the paper the holes necessary for binding. To this end the drill is inserted into one of the openings 23, the advancement of the drill through the hole therein and through the block of paper thereunder being guided and determined by the boss which extends upwardly from the plate. By proceeding in this manner, the necessary number of holes may be provided in the edges of the paper. It is, of course, feasible to employ a multiple punch or drill press operated by suitable levers or power which can perform this operation, but in the embodiment shown, a simple and inexpensive boring outfit, such as the hand drill mentioned, is capable of being used. The openings 23 and bosses 22 are convenient to assist in guiding an implement, but in some cases may be found unnecessary, so that a plate 20, on which no such bosses are formed or which embodies a slot construction similar to that in the plate 17, may perhaps be advantageously utilized.

50 If the paper leaves to be bound are, prior to insertion in the present device, provided with alining holes for binding purposes, the operation of drilling or punching holes in the manner described will not be necessary, 55 of course. Suitable cords or other tying means are strung through the openings and tied permanently while the paper is still

compressed, the sections of cord which overlie the outer edges of the paper slipping into position through the slots 24. Thereafter, 60 the pressure is removed by manipulating the thumb screws in the proper direction and the leaves are removed in bound form as a separate book.

65 I claim:

1. A book binding appliance comprising a base on which a quantity of leaves may be stacked, the base being formed with a groove in the upper surface thereof, means for evening the leaves prior to binding consisting of a block arranged perpendicularly to the base and movable thereon, and a member secured to the block and arranged to maintain the block in perpendicular relation to the base, a portion of the said member being 75 arranged to lie within the base groove beneath the leaf stack, and means for securing the block in a selected fixed position of adjustment upon the base, substantially as described.

2. A book binding appliance comprising a base on which a quantity of leaves may be stacked, means for evening the leaves prior to binding consisting of a block arranged perpendicularly upon the base and movable 85 with respect thereto, and a member arranged to maintain the block in perpendicular relation to the base, the said member being provided with ratchet teeth arranged to engage with the base, there being complementary ratchet teeth upon the base for engaging therewith to prevent retractive movement of the block from a selected position upon the base, substantially as described.

95 3. A book binding appliance comprising a base on which a quantity of leaves may be stacked, means for evening the leaves prior to binding comprising a block arranged perpendicularly to the base and movable thereon, and a member arranged to maintain the block in perpendicular relation to the base secured to the block and in engagement with the base, the said member being partially disposed beneath the stack of leaves whereby the weight of the leaf stack serves to hold the member perpendicular to the base, and means for preventing retractive movement of the block upon the base, substantially as described.
